UNITED STATES PATENT OFFICE.

STANLEY P. THOMPSON, OF SEATTLE, WASHINGTON.

INTEREST-COMPUTING MACHINE.

1,311,100.

Specification of Letters Patent. Patented July 22, 1919.

Application filed December 14, 1917. Serial No. 207,195.

To all whom it may concern:

Be it known that I, STANLEY P. THOMPSON, a citizen of the United States, and resident of the city of Seattle, county of King, 5 and State of Washington, have invented certain new and useful Improvements in Interest-Computing Machines, of which the following is a specification.

My invention relates to computing devices and consists of an apparatus which may be employed for computing interest at various rates and for various times.

The object of my invention is to provide a device such that the interest due on any 15 amount may be determined thereby through the addition only of sums which will be indicated by the operation thereof, it being possible to in this way find the interest on any amount for any time, at any rate.

20 My invention comprises the novel parts and combinations thereof which will be hereinafter described and then particularly pointed out in the claims.

In the accompanying drawings I have 25 shown my device embodied in the type of construction which is now most preferred by me.

Figure 1 is a face view of one of the indicating faces of my device.

30 Fig. 2 is a cross section of the same showing the operating parts contained therein.

Fig. 3 is an end view of the device showing the end containing the knobs by which it is operated.

35 Fig. 4 is a vertical longitudinal section on a larger scale through one end of the companion pair of rollers.

Fig. 5 is a detail showing the end of one 40 of the roller shafts upon which the stop device for limiting its turning is mounted.

Fig. 6 is a cross section through the nut which is mounted upon this end of the shaft.

Fig. 7 is a cross section of the shaft showing the manner of mounting the stop therein.

Fig. 8 shows a short section of the web and the figures thereon.

In carrying out my invention I provide a certain number of webs 1, these being made 50 of paper, or other like material, and having printed thereon certain columns of figures, one of which, as the left hand one, which is lettered 10, represents certain amounts of principal upon which interest 55 is to be determined. Another, 11, adjacent thereto, represents the interest rate and

each of the series of columns 12 represents the interest on the principal at the given rate for a certain length of time, which length of time is indicated by figures 13 60 which are placed upon a fixed member which aligns with the columns of the web and which represents the number of days upon which the interest runs.

In Fig. 8 I have shown a short section 65 of one face of a web. This shows eleven columns, each of which has its figures transversely alined so as to form lines. As stated, the first column represents the principal, the second, which might be omitted 70 if a single rate of interest only was shown on the face of the web, represents the rate of interest, and the other columns the amount of interest for its principal amount for a certain number of days. 75

As shown in Fig. 8, and as I contemplate showing it in most cases, the interest for two different rates are shown upon the same side of the web, these rates alternating. That is, for each principal amount the interest for the two rates are placed in alternate and successive lines, that is, for example as shown in Fig. 8, the interest is shown on one face for 5% and 7%, one line being for 5% and the next for 7%, and both 80 lines being associated with the same principal amount.

I contemplate having these webs printed upon both sides, the mechanism being so constructed that one side is exposed at one 90 side of the casing in which the mechanism is mounted, and the other side of the web is exposed at the other side of the same casing. It is thus possible to show four different rates of interest upon the same web. 95 I have chosen for the present case to show the interest at 5%, 6%, 7%, and 8%.

The casing 2 has a window opening 20 at two opposite sides centrally placed in the width of the sides. This opening extends 100 the length of the casing and has a glass plate 21 inclosing the same. Within the casing are placed rollers to which the ends of the web are secured. These rollers are arranged in pairs, the rollers 3 having one end of a 105 web secured thereto and the rollers 30 having the other end of the same web secured thereto. The companion rollers to which the ends of the same web are secured, are arranged one above the other and are provided 110 with gear wheels 31 connecting them so that they are compelled to turn together.

In connection with each pair of rollers I also provide two small idler rollers 4, these being mounted close to the inner faces of the glass 21, at opposite sides of the casing 5 2. The web leading from a roller 3 first passes over the idler roller 4 which is at that side of the casing, thence back into contact with the opposite side of the roller 3, about one side of the roller 30, thence to the idler 10 roller 4 at the other side of the casing, back to the roller 30 to which this end thereof is secured. In this manner the two sides of the web are exposed, one at one side of the casing and the other at the other side. 15 The inner surface of the glass 21 is provided with a surface which is opaque except for certain slots through which one line of the figures of the web 1 may be seen. This coating 22 is preferably made of paper and 20 has the slots 23 cut therein of a width to render a line on the web visible. This paper also has the figures 13 printed thereon, said figures indicating the number of days for which the interest is to be calculated, the 25 number of days corresponding with the interest rates shown in the corresponding column of the web. 30 Figures 13, which indicate the time element, are placed upon the paper 22 in such position as to indicate the point where the decimal point is to be placed in the interest amount shown on the web. The figures 13, as shown in the drawings, are all in multiples of one hundred. Where the interest is 35 for an exact number of hundreds of days, the decimal point is to be placed in the figures 14, the same being the columns wherein the amount of interest is shown, directly under or in alinement with the right end of 40 the figures representing the time. If the time is only ten days then it is evident that the decimal point will be shifted one point to the left and for one day it will be shifted one more point to the left. Contrariwise, if 45 the time should be one thousand days, the decimal point would be shifted one point to the right. In this way it is possible to determine the amount of the interest for any number of days. 50 Taking the device with the setting shown in Fig. 1, the principal amount as shown by the uppermost line is \$610,000; the principal amount, as shown by the second line, is \$4800; while the principal amount as shown 55 by the lowermost line is \$15. Therefore, if we use all of these three lines for our purpose, the total principal amount indicated by the columns showing the amount of principal will be \$614,815.00. To obtain the 60 interest on this amount for one hundred days we will, therefore, add the indications shown in the three lines. The upper line would give us \$11,861.11, this being the interest on \$610,000 at 7% for one hundred days. 65 The second line would give us \$93.33, as the

interest on \$4800 at 7% for one hundred days, while the third line would give us \$29 as the interest on \$15.00 at 7% for one hundred days. The sum of these amounts which is \$11,954.73, is obtained by adding 70 the interest amounts shown in the three lines for the time of one hundred days, which gives us the interest on the total amount.

The number of lines placed upon the web are sufficient so that the interest may 75 be obtained on any amount from \$1.00 to \$999,999.00, at any rate for which the interest has been figured. In the device as shown, this would be for 5%, 6%, 7% and 8%. If interest at other rates is desired, this may be 80 obtained by multiplication or division. For instance, at 4% the interest at 8% would be determined and this amount divided by two.

Likewise, for 3½% the interest at 7% 85 would be determined and this amount divided by two. In many cases where the amounts are in exact hundreds or thousands, it may be necessary to read only from one or two of the lines. 90

To prevent over-turning of the rollers 3 and 30, to which the webs 1 are secured, I have provided a stop device which is shown in Figs. 5, 6, and 7. By this device I provide one of the shafts 32, upon which the 95 rollers 3 and 30 are mounted, with a threaded section 33, at one end. This threaded section projects beyond the gear 31 for this roller. Mounted upon this threaded section 33 is a nut 5, which nut should be held 100 against rotation in some manner. The manner of doing this herein shown consists in providing the nut at opposite sides with slots 50, in which are placed the arms 60 forming extensions of a plate 6, which plate 105 is provided with a hole through which extends a pin 61, which is secured to the frame. The nut and its attached arm 6, are thus moved lengthwise of the shaft 32, as it is actuated by the turning of the shaft. 110

To secure stoppage of the shaft 32 against rotation without jamming of the nut, I employ pins 34 located one at each end of the threaded section 33, these pins being placed squarely in the hollow between 115 threads, and coöperating shoulders 51 formed at each side of the nut by cutting away one of the threads. This provides radial stop surfaces on both shaft and nut, so that there can be no jamming of the nut. 120

By reason of providing a positive stop movement of this sort for turning of the roll, the danger of loosening the attachment of the paper web thereto is avoided. It is, of course, evident that other means for securing this result might be provided. The means just described are the means I now prefer to use.

I also prefer to mount one of the rolls 3 in such a manner that it may yield a little 130

in its rotation. This is desirable by reason of the fact that the piling of the web upon itself as the web is turned, so as to expose one end thereof, makes the rollers somewhat unequal in diameter. It is to accommodate this tendency that I prefer to mount one of the rolls so that it may yield.

One manner of doing this and that now preferred by me, is shown in Fig. 4. The 10 rolls 3 are herein shown as hollow, although the roll 30 might as well be made solid, if desired. Within the roll 3 is, however, mounted a torsional spring 7, which spring 7 is connected at one end with the shaft 32, 15 as is shown at 70, and at its other end is connected with the roll 3. Therefore, the rotative effort between the gear 31 and the roll 3 is communicated through the spring 7, thus permitting a slight turning movement 20 between the gear and the roll, thus accommodating for the differences in diameter in the rolls which is produced by the piling of one end of the web upon itself upon the roll.

25 It may be desired to adjust the initial tension of the spring 7. This may be secured in the following manner:

The ends of the shafts 32, which are opposite to that upon which the gears 31 30 are secured, project through the end walls of the casing 2 and are preferably provided with knobs or wheels 35 by which they may be conveniently turned. If these knobs be made removable from the shafts, as may 35 be done by securing them thereon through the means of a pin, and if then one of these shafts be pushed inward until the gear 31 secured thereto has been disengaged from the intermeshing gear 31, the gear 31, which 40 is associated with the roll in which the spring is contained, may be turned so as to increase or decrease the initial tension upon the spring 7. In this manner the tension upon the spring 7 may be adjusted. It may 45 be noted that the gears 31 are secured against turning upon the shafts 32.

I prefer to provide the gears 31, especially those which are mounted upon the shaft which is movable in order to adjust 50 the tension of the spring, with an internal flange 36 or equivalent ears, so that when the gear is moved outward in order to disengage it from its companion gear, the flange will not be entirely removed from the 55 tubular roll 3.

In the device as herein shown I have employed three sets of rolls 3 and 30, and three sets of idler rolls 4. This slot should be of such a width as to show but one line 60 of figures upon the web except possibly at the left hand end where the principal amounts are shown. This slot may be made of double width at this point in such cases wherein two different interest rates are 65 shown on the same face of the web. This

permits view of the principal amount when the web is turned for either of the interest rates which are shown upon the web. In lieu of this the principal amount may be duplicated upon the web.

70 For convenience in using this device I prefer to mount it in such manner that it may be bodily turned upon a pivot axis so as to bring either of the two sides which are to be inspected uppermost. A manner 75 of doing this and the one which I now prefer to use is shown and consists of the following.

At one end of the case, being the end at which the knobs 35 are secured to the shafts, 80 I provide the end of the casing with a circular flange ring 8. A base 9 is provided with a pair of rollers 90 upon which the flange ring 8 rests. To prevent removal of the flange ring the base 9 may have flange 85 sections 91 which project over the flange ring 8. At the opposite end of the casing a single pivot axis 92 may be secured to the end of the casing, this being journaled in an upright frame formed by the two bars 90 93. The two end portions of the base may be connected by bars 94. For convenience the two parts of the standard may be disengageably connected, as by means of bolts or screws 95. In this manner the casing 95 may be conveniently turned so as to bring either side in an uppermost position and also to adjust it in angular position, as in Fig. 3. This position will in many cases be found desirable and convenient in the use 100 of the device.

What I claim as my invention is:

1. An interest computing device comprising a casing having a plurality of related webs therein, sight openings formed in the 105 casing and means for causing the webs to traverse the said sight openings said webs each having a column of figures indicative of principal amounts and a plurality of columns of figures indicative of interest 110 amounts upon said principal amounts for varying periods of time and figures upon the casing indicative of the numbers of days said latter figures having the several units thereof so disposed with relation to the 115 units constituting the interest amounts as to indicate where the decimal point will fall in determining the interest for units, tens, or hundreds of days.

2. In a device of the character described 120 the combination with a casing having a sight opening, of a plurality of indicia carrying webs therein carrying columns of figures indicative of principal amounts and columns indicative of interest amounts relating thereto, figures indicative of hundreds of days carried by the casing in alignment with the latter columns, rollers of considerable size over which said webs travel 125 and by which movement is imparted to the 130

webs and guide rollers of much smaller diameter than the first named rollers arranged in proximity to the sight openings and close together so that a plurality of items of like nature upon the several webs will be brought into such proximity as to permit them to be conjointly read and added.

3. An interest computing device comprising a casing having a sight opening, a plurality of webs therein means for causing said webs to traverse said sight opening, each of the webs having a column of figures representing principal amounts, the said columns of the several webs differing in decimal values, a plurality of columns upon each web representing interest amounts upon the principal amounts carried by the web, said columns being vertically disposed and the said interest amounts alined horizontally with the principal amounts to which they relate and the different columns of interest amounts differing in respect to the time for which the interest is figured, and time indicating figures upon the casing, the columns of interest amounts upon the several webs alining vertically beneath the time indicating figures to which they relate whereby they may be added in the usual manner, time indicating figures having the units of which they are composed so related to the units composing the interest amount

as to indicate by their position where the decimal point is to fall in the latter amount according to the number of days for which interest is to be determined.

35

4. An interest computing device comprising a casing having a sight opening in each side thereof, a plurality of webs mounted in said casing for traveling movement past said sight openings one side of each web being exposed to view at one side of the casing and the other sides of said webs being exposed to view at the other side of said casing said webs carrying matter of a nature requiring the amounts upon the several webs to be added.

40

5. In a device of the character described the combination with a plurality of webs carrying matter of such nature as to require the complementary consideration thereof, a casing in which said webs are mounted, sight openings in the opposite sides of said casing, a mounting for said casing which permits the same to be bodily rotated and guide means for said web of such nature that the opposite sides of the several webs are exposed to view at the respective sight openings.

50

Signed at Seattle, Washington, this 8th day of December, 1917.

STANLEY P. THOMPSON.
